G. W. WILDIN

ANGLE COCK DEVICE

Filed May 12, 1925

Fig. 3.

INVENTOR
GEORGE W. WILDIN

BY *Wm. H. Cady*
ATTORNEY

UNITED STATES PATENT OFFICE.

GEORGE W. WILDIN, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ANGLE-COCK DEVICE.

Application filed May 12, 1925. Serial No. 29,664.

This invention relates to fluid pressure controlling means and more particularly to an angle cock device for controlling the flow of fluid under pressure through the brake pipe on railway trains.

The standard angle cock, now in general use in connection with fluid pressure braking systems on railway trains, comprises a cock body in which is vertically disposed a tapered plug valve. The small end of the plug valve extends out of the cock body and is adapted to receive an operating handle, while the large end of said plug valve is exposed to the pressure of fluid in the brake pipe and to the pressure of a coil spring.

Considerable pressure acting on the large end of the plug valve is necessary in order to ensure the tight seating of the plug valve, so as to prevent leakage, but said pressure also functions to create a great amount of resistance to rotative movement of the plug valve from one position to another, which, as will be evident, is undesirable.

The principal object of my invention is to obviate the above difficulty by providing an angle cock in which the pressure acting to resist the turning movement of the plug valve is automatically relieved during the period when said plug valve is being rotated from one position to another.

In the accompanying drawing, Fig. 1 is a sectional view of an angle cock device embodying my invention; Fig. 2 a plan view of the angle cock device; and Fig. 3 a fragmentary front elevational view of the angle cock device.

As shown in the drawing, the angle cock device may comprise a cock body 1 having a conduit 2 and a tapered opening for receiving the usual tapered plug valve 3, which is provided with a connecting port 4. The portion of the body casting surrounding the upper end of the tapered opening extends upwardly and is provided with an outwardly extending annular flange 5.

A cap plate 6 is mounted on the flange 5 and is provided with diametrically opposite downwardly extending lugs 7 and 8, each having a recess for receiving the flange 5. In order to apply the cap plate 6 to the flange 5, said flange is provided with opposite slots 9 and 10, which are located at an angle to the position which the lugs 7 and 8 assume when the plug valve 3 is in open or closed

positions, so that when the lugs 7 and 8 are inserted in slots 9 and 10 and the cap 6 rotated to assembled position, the recesses in said lugs will engage the flange 5 in both open and closed position of plug valve 3.

Engaging the rectangular key portion of the plug valve 3 and free to move vertically thereon is a member 11, which extends through a central opening in the cap plate 6.

A lug 12 extends upwardly from the plate 6 and an operating handle 13 is pivotally mounted thereon by means of a pivot pin 14. The inner end of the handle 13 is forked and encloses a raised portion of the member 11, so that said member and consequently the plug valve 3 are operable by the handle 13. In order to lock the handle 13 in its operating positions, a tang 15 is provided on said handle and is adapted, in the open position of the plug valve 3, to engage a slot 16 in a quadrant 17 cast on the cock body 1, and in the closed position of said plug valve to engage a slot 18 in said quadrant. The forked ends of the handle 13 are provided with cam surfaces, which are adapted to engage the outer face of the member 11 so as to depress said member when the handle 13 is raised.

A coil spring 19 is mounted in the chamber at the large end of the plug valve 3, and a spring plate 20 having a concave recess on one face engages said spring at its opposite face. A rocker plate 21 having a corresponding convex projection 22 engaging the recess in the spring plate 20, is interposed between the spring plate 20 and the under face of the plug valve 3.

In order to relieve the plug valve 3 of the pressure of spring 19, I provide two pins 23 and 24, which engage corresponding recesses in the rocker plate 21 and extend through parallel bores in the plug valve 3 and cap plate 6 so as to engage the inner face of the member 11 at diametrically opposite points. A small coil spring 25 interposed between the rocker plate 21 and the plug valve 3 acts to prevent unseating of the plug valve, when it is relieved of the pressure exerted by the spring 19.

When it is desired to move the plug valve 3 from closed to open position, the handle 13 is first raised so as to disengage the tang 15 from slot 18 in the quadrant 17, so as to release the handle to permit of turning same. This movement of the handle 13 also acts to

bring the cam surfaces of the forked portion of said handle into engagement with the outer face of member 11 so as to depress said member, which acts through the pins 23 and 24, rocker plate 21 and spring plate 20 to compress the spring 19, thereby relieving the plug valve 3 of the pressure of said spring. The handle 13 is then rotated in a clockwise direction until the tang 15 engages slot 16 in the quadrant 17, at which time the port 4 will have established communication through the conduit 2. It will be evident that the device will operate in a like manner in moving the plug valve from open to closed position.

Having now described my invention, what I claim as new and desire to secure by Letters Patent, is:

1. A valve body, a plug valve mounted in said body, a spring acting on said valve, an operating handle for said valve, and means operated by said handle for relieving the valve of the pressure of said spring.
2. A valve body, a plug valve mounted in said body, a spring acting on said valve, a pivoted handle for operating said valve, and means operated upon pivotal movement of said handle for relieving the valve of the pressure of said spring.
3. A valve body, a plug valve mounted in said body, a spring acting on said valve, and means for automatically relieving the valve of the pressure of said spring upon operation of said valve.
4. The combination with a valve body and a tapered plug valve mounted therein, of a spring acting on said valve for maintaining the valve seated, a pivoted handle for operating said valve, and means operated upon a pivotal movement of said handle for relieving said valve of the pressure of said spring.
5. The combination with a valve body and a tapered plug valve mounted therein, of a spring acting on said valve for maintaining the valve seated, a handle for operating said valve, means for locking said handle in an operating position of the valve, and means operated upon unlocking said handle for relieving said valve of the pressure of said spring.

6. The combination with a valve body and a plug valve mounted in said body, of a spring acting on said valve and tending to seat the valve, a movable member interposed between said valve and said spring, an operating handle for said valve, and means operated by said handle for moving said member, to thereby relieve the valve of the pressure of said spring. 55

7. The combination with a valve body and a plug valve mounted in said body, of a spring acting on said valve and tending to seat the valve, a handle for operating said valve, means operated by said handle 65 for relieving the valve of the pressure of said spring, and an additional spring also acting on said valve for maintaining the valve seated, when the valve is relieved of the pressure of the first spring. 60

8. The combination with a valve body and a plug valve mounted in said body, of a spring acting on said valve and tending to seat the valve, a movable member interposed between said valve and said spring, an operating handle for said valve, means operated by said handle for moving said member to thereby relieve the valve of the pressure of said spring, and a spring interposed between said valve and said movable member. 75

9. The combination with a valve body and a plug valve mounted in said body, of a spring acting on said valve and tending to seat the valve, a movable member interposed between said valve and said spring, pins engaging said member and extending through openings in said valve, an operating handle for said valve, and means operated by said handle for moving said pins and thereby 85 said member. 90

10. The combination with a valve body and a plug valve mounted therein, of a vertically movable handle for rotating said valve, a spring acting on said valve, and means operated by the vertical movement of said handle for relieving the valve of the pressure of said spring. 95

In testimony whereof I have hereunto set my hand.

GEORGE W. WILDIN.
